UNITED STATES PATENT OFFICE.

HENRY A. SCHAEFER, OF ROCHESTER, NEW YORK, ASSIGNOR TO SCHAEFER & SCHLEGEL, OF SAME PLACE.

DESIGN FOR TRIMMING.

SPECIFICATION forming part of Design No. 32,243, dated February 13, 1900.

Application filed January 2, 1900. Serial No. 176. Term of patent 7 years.

To all whom it may concern:

Be it known that I, HENRY A. SCHAEFER, a citizen of the United States, residing in the city of Rochester, county of Monroe, and State of New York, have invented and produced a new and original Design for Trimming, of which the following is a specification, reference being had to the accompanying drawing, forming a part thereof.

The design illustrated in the drawing embodies the heading A and the loosely-hanging threads forming the fringe B, and the former is composed of the edging *a* and the parallel strip *b*, slightly narrower in width than the edging *a* and separated from the latter by

the open-work C, said open-work giving to the eye the impression of separate loops formed of double threads or cords on the proximate edges of the portions *a* and *b* and interlocking, as shown.

20

Having described my design, what I claim as new, and desire to secure by Letters Patent, is—

The design for a trimming, substantially as herein shown and described.

HENRY A. SCHAEFER.
